UNITED STATES PATENT OFFICE

MATTHEW K. SCHILLING, OF NEW ORLEANS, LOUISIANA

BOX

Application filed September 18, 1929. Serial No. 393,497.

This invention relates to knock-down boxes and has for its object the provision of a box which may be easily set up or taken apart and in which the sides will be reinforced when in use and the top and bottom will be accurately centered to facilitate the proper assembling of the same with the sides. The invention also has for its object the provision of novel means for locking the top and bottom in place. The invention is illustrated in the accompanying drawing and will be herein-after fully set forth.

In the drawing:

Figure 1 is a perspective view of my improved box arranged for use.

Fig. 2 is an enlarged perspective view of the corner post, and

Figs. 3 and 4 are enlarged detail sections showing the manner of locking the top and bottom in place.

In carrying out the invention, there is provided a plurality of side members 1 which may be of any light inexpensive material, such as cardboard, and which may be formed in one integral structure to be collapsed when the device is not in use or may be separate elements each having the dimensions of one side of the contemplated box. The side members rest upon a bottom 2 which may be of light boards or wooden material but may be of one or more plies of heavy cardboard. The bottom is preferably of rectangular outline and at its corners is notched, as shown at 3, to accommodate a corner post 4. It will be understood that the side members rest at their lower edges on the bottom near the margins thereof, and a top 5 is rested on the upper edges of the side members, the top, like the bottom, having notches 6 at its corners to receive the upper portions of the corner post 4. The corner posts, as shown most clearly in Fig. 2, may be of stout wire or light rods and each post has a head 7 at its lower end whereby it is adapted to retain coils 8 thereon. The upper end of each post is carried laterally, as at 9, to extend over the top 5 and at the end of this lateral arm or extension is formed into a depending spur or hook 10 adapted to enter an opening 11 provided therefor in the top whereby the top

will be firmly held in place. A plurality of coils 8 are mounted upon each corner post and these coils are disposed in superimposed relation so that each coil, except the lowermost, will be supported by the coil immediately below it, the lowermost coil, as stated, being supported by the head 7. From the lowermost coil extends a lateral arm 12 which passes under the bottom 2, as shown in Fig. 4, and has its terminal formed into an upward eye 13 which passes up through an opening 14 provided therefor in the bottom. A securing ring 15 is engaged through the eye 13 and rests upon the bottom 2, as shown in Fig. 4, whereby to retain the eye in engagement with the bottom. From each upper coil 8, the wire forming the same is extended along the side of the box, as shown at 16, to the opposite corner and is there formed into a corresponding coil 8 so that a reinforcement is provided against the outer surface of each side member of the box and which reinforcement terminates at both ends in a coil encircling the respective corner posts. The top 5 may be provided with a handle 17 of any approved form to facilitate the carrying of the box.

The box is shown as arranged for the shipping of eggs and it is the intention that the box be returned to the original shipper in a knock-down condition, but, of course, any desired merchandise or articles may be disposed within the box, the proportions of the box being varied as may be needed to meet the conditions of any particular use. For shipping eggs, the usual collapsible cells are provided consisting of partitions 18 and pocket diaphragms or plates 19 having pockets 20 formed therein at regular intervals to be disposed within rectangles defined by the partitions when the parts are assembled. The pockets 20 in the lowermost plate serve not only to provide cups in which the eggs may seat but also space the plate above the bottom of the box so as to accommodate the fastening ring 15 and the eye 13.

In assembling the box, the corner posts with the coils and reinforcing wires carried thereby are engaged at their lower ends in the notches at the corners of the bottom and the

arms 12 are extended under the bottom and their terminal eyes inserted upwardly therethrough after which the locking rings 15 are engaged in said eyes, as will be understood. 5 The side members, whether separate pieces or a continuous creased strip, are then set on edge upon the bottom against the reinforcing wires and the top or lid is then imposed upon the sides, the notched corners being easily engaged with the upper portions of the posts. 10 The retaining arms or extensions 9 are then swung over the top so that the hooked ends 10 thereof may be engaged in the openings 11 in the top to secure the latter in place. To 15 collapse the box, the hooks 10 are withdrawn from the openings 11 and the arms 9 then swung out beyond the margins of the top which may then be lifted from the box. After the contents of the box are removed, the retaining arms 12 are released from the bottom so that the side reinforcements may be folded together and placed flat upon the bottom, and the side members may be collapsed with and remain within the wire frame. The 20 top may then be placed over the reinforcements so that a flat bundle will be produced and the parts may be secured against separation in their disassembled or knock-down condition by being tied with stout twine or by 25 any other well known means. It will be understood, of course, that in collapsing, the wire frames rotate on the corner posts.

The device is especially desirable for shipping goods, such as shoes, which are placed in cartons, as it provides excellent protection to the cartons to prevent crushing thereof, and several collapsed boxes may be made into one bundle and returned to the consignor at a great saving in shipping costs.

40 Having thus described the invention, I claim:

1. A box comprising a top, a bottom and side members, corner posts adapted to engage the top and bottom at the corners of 45 the same, and reinforcements extending from and between the corner posts to bear against the outer surface of the sides.

2. A box comprising a top, a bottom each having notches at its corners, corner posts 50 engaged in said notches, means carried by the ends of the posts to engage the top and bottom and retain them in position, sides disposed between the top and bottom, and reinforcements carried by and between the 55 posts against the outer surfaces of the sides.

3. A box comprising sides, a top and a bottom each having notches at its corners, posts engaged in the corner notches of the top and bottom, means at the ends of the posts to 60 retain the top and bottom in place, coils encircling the posts, and reinforcing strands connecting and extending between corresponding coils at adjacent corners.

4. A box comprising sides, a top and a 65 bottom each having notches at its corners,

posts seated in the notches in the top and bottom, a retaining arm extending laterally from the upper end of each post and having its terminal turned downwardly to engage an opening in the top whereby to hold the top in place, and means carried by the lower ends of the posts to retain the bottom in place.

5. A box comprising a top, a bottom each having notches in its corners, sides disposed between the top and the bottom, posts seated in the notches at the corners of the top and bottom, means at the upper ends of the posts to retain the top in place, heads at the lower ends of the posts, retaining arms fitted upon the posts and supported by said heads and extending under the bottom of the box, eyes at the free ends of said arms adapted to extend upwardly through the bottom, and retainers engaged through said eyes and resting on the bottom.

In testimony whereof I affix my signature.
MATTHEW K. SCHILLING. [L.S.]
